UNITED STATES PATENT OFFICE.

RALPH V. L. HARTLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

CARRIER-WAVE TRANSMISSION.

Application filed August 12, 1921. Serial No. 491,686.

This invention relates to carrier wave transmission and more particularly to composite power current and carrier wave transmitting systems.

5 An object of the invention is to provide an arrangement for selecting carrier waves of small amplitude from very large amplitude power currents of different frequency as well as from the principal harmonics of 10 these power currents.

A further object of the invention is to prevent the application of dangerously high electromotive forces to carrier wave apparatus associated with high tension electric 15 power transmission conductors.

20 A feature of the invention consists in relating the carrier wave terminal apparatus to the power transmission system by selective transmitting devices which serve the two functions of selecting the carrier waves 25 from the power currents and of protecting the carrier wave apparatus from dangerous potentials which might otherwise be set up therein.

25 According to this invention, a high voltage power transmission line is utilized for simultaneous transmission of signal modified carrier waves. The apparatus for producing the carrier waves and the apparatus 30 for receiving incoming carrier waves are associated with the transmission line through a transformer of low mutual inductance and a high pass filter which interposes several 35 series condensers in the circuit, thus minimizing any tendency to set up dangerously high intensity E. M. F.'s across elements of the carrier wave apparatus.

The drawing illustrates one terminal of a 40 system embodying the invention in which a multiplex carrier wave signaling system is composed with a three-phase alternating current power transmission system.

45 Referring to the drawing, a three-phase alternating current source 1 is associated with a three-phase transmission line 2 by means of a transformer 3. A plurality of ordinary two-way telephone or other signaling lines 4 of which one only is illustrated are associated with the power transmission line 2 by means of carrier wave terminal apparatus. The carrier wave terminal apparatus comprises a carrier wave transmitting channel 5, and a carrier wave receiving channel 6 for each signal line 4,

an outgoing transmission filter 7, and an 55 incoming transmission filter 8, common to all of the signal lines 4, and a high pass filter 9 through which all of the carrier wave terminal apparatus is associated with the ground conductor 10 connected to the electrical mid-point of the three-phase transmission line.

Considering the transmission path for each signal line 4 in detail, it may be noted that the signal line is provided with the 65 usual balancing network N which is so designed as to simulate the impedance of the line 4 at the frequencies of all the currents transmitted thereover. The signal line 4 is connected to the transmitting channel 5 and 70 receiving channel 6 by a balanced transformer or hybrid coil 11 of well known type. Outgoing currents or impulses originating in line 4 are impressed upon carrier transmitting channel 5 which includes the 75 low pass filter 12. This filter is preferably of the type described in the paper entitled "Carrier current telephony and telegraphy"

at pages 311 and 312, vol. 40, No. 4, Journal of the American Institute of the Electrical 80 Engineers, April, 1921, and is preferably designed to pass currents of all frequencies below a fixed cut-off frequency as, for example, 2500 cycles in the case of telephony, and to supply currents which it transmits to a 85 modulator 13. Associated with the modulator is an oscillator 14 which serves to supply to the modulator carrier waves to be modulated in accordance with the currents originating in signal line 4. This oscillator 90 and modulator may be of any desired type as, for example, that shown in Fig. 9, at page 306, of the article "Carrier current telephony and telegraphy", previously cited.

95 The modulated carrier current from modulator 13 is impressed upon a transmitting filter 15 which may be designed to transmit currents of a range of frequencies including both side bands of a modulated carrier wave or may transmit only one side band and the unmodulated carrier wave component. Each of the other signal lines 4 is associated with a carrier wave transmitting channel similar to 5, and differing therefrom only in that the frequency of the oscillator is sufficiently 100 different from the frequency of each of the other oscillators to prevent interference between the modulated bands passed by the 105 receiving channel 6.

transmitting filters TF_1 , TF_2 , etc. The various modulated carrier waves are transmitted by a transformer 16 to a high pass filter 7, which serves to pass waves of the outgoing transmissions and to exclude waves of the incoming transmissions. High pass filter 7 is connected through the transformer 17 to a high pass filter 9 which serves to separate carrier waves from the alternating current power waves. A high pass filter is one which operates to freely transmit currents of all frequencies above a fixed frequency known as the cut-off frequency and to substantially suppress currents of all frequencies therebelow. Filter 9 also serves to interpose a plurality of series condensers in the carrier transmission circuit, and any high voltage which might be impressed across its outer terminals is accordingly distributed over a plurality of elements of the filter, thus preventing a dangerous potential accumulating across any one element. The filter 9 is associated with the grounded conductor 10 by transformer 18, which has low mutual inductance between its windings. If the three-phase alternating current system is properly balanced there will be no flow of power current in the ground conductor 10. If, however any power current should flow in this conductor in consequence of unbalance in the power transmission line, the mutual inductance of transformer 18 is too low to permit any appreciable transfer of the low frequency power current energy by this transformer to filter 9.

The carrier frequency oscillations may be of much higher frequency than the alternating power currents, and may therefore be readily transmitted by the transformer 18. For carrier wave transmission, three conductors of transmission system 2, operate in parallel as a single conductor with a ground return through conductor 10. Incoming carrier waves impressed upon filter 9 by transformer 18 are supplied to the secondary winding of transformer 17. The incoming carrier waves at the station illustrated are of lower frequency than the outgoing carrier waves. Low pass filter 8 is preferably so designed as to readily transmit the range of currents below that transmitted by filter 7. The received carrier waves are therefore selected by filter 8 and transmitted by a transformer 19 to a circuit including the receiving filters RF_1 , RF_2 , RF_3 , etc. Each of these filters is designed to select modulated waves of a band corresponding to that transmitted by a cooperating transmitting filter at the remote carrier terminal apparatus and to exclude currents of other frequencies. The carrier waves selected by one of these filters as, for example, RF_1 are supplied to a demodulator which yields in its output circuit, currents of the same frequency and wave form as those which origi-

nated in the remote signal line 4. These demodulated signal currents are impressed upon the local signal line 4 through a low pass filter 20, similar to filter 12, and which serves to exclude all currents of higher frequency. 70

It will, of course, be understood that the invention is applicable, generally, to carrier wave transmission of any character over power transmission conductors whether for signaling purposes or not. If, however, the system is to be used for multiplex carrier wave telephony, telephone and other signaling currents within the frequency range of zero to 2000 cycles may be impressed upon each local signaling circuit 4. The carrier wave oscillators 14 for the outgoing transmissions may be given frequencies of 15,000, 18,000 and 21,000 cycles, respectively. The filter TF_1 may be designed to transmit a band of frequencies extending from 14,950 cycles to 17,000 cycles, thus including both the unmodulated carrier wave component, and the upper side band of the modulated carrier wave. The filter TF_2 may be given a range of 17,950 cycles to 20,000 cycles, and the filter TF_3 from 20,950 to 23,000 cycles. The filter 7 may be designed to pass currents of all frequencies above 14,950 cycles and filter 8 to pass currents of all frequencies below 12,050 cycles. The receiving filter RF_1 may transmit a band of currents from 10,000 cycles to 12,050 cycles inclusive; filter RF_2 , from 7,000 cycles to 9,050 inclusive, and RF_3 , from 4,000 to 6,050 inclusive. Filter 9 may therefore be designed to pass currents of all frequencies above 4,000 cycles and to exclude currents of all frequencies below this frequency. Since the frequencies of power currents are ordinarily 25, 50 and 60 cycles, it will be clear that filter 9 will exclude not only the fundamental frequency power currents, but also a large number of the harmonics including all those of considerable amplitude. 100 105 110

The apparatus at the remote terminal of the transmission system 2 is similar to that illustrated with the exception that the outgoing transmission at the remote terminal is at lower carrier frequencies than the incoming transmission. In the example given in which the frequencies of the carrier waves transmitted from the local station are respectively 15,000, 18,000 and 21,000 cycles, the frequencies of the carrier waves transmitted from the remote terminal apparatus may be 6,000, 9,000 and 12,000 cycles, respectively. It will be necessary at the remote station to associate the high pass filter 7 with the carrier receiving channels and the low pass filter 8 with the carrier transmitting channels and to interchange the transmission ranges of the filters TF_1 and RF_1 , TF_2 and RF_2 , etc. 115 120 125

Although the invention has been disclosed 130

as embodied in a specific system, it is to be understood that various features are applicable to transmission systems generally.

What is claimed is:

- 5 1. A power line communication system comprising a power line, a signaling circuit and means, for connecting the signaling circuit to the power line, comprising a path, conductive to direct current, connected to a neutral point of a three-phase power transformer, a signal wave transformer for waves of a frequency above the usual audible range and having mutual inductance between its primary and secondary windings lower than that of an ordinary speech frequency transformer connected in said path, and a filter, having series capacity and shunt impedance, connecting said transformer to said signaling circuit.
- 10 2. A circuit for duplex or two-way communication over a high tension power line comprising signal transmission and reception paths, respective transmitting and receiving filters for said paths, selective of waves in different frequency bands, a third filter for freely transmitting waves in the bands selected by said first mentioned filters and excluding waves of certain other frequencies, connections highly effective for transferring signaling waves but of less effect for transferring waves of power frequencies, for coupling said third filter to said power line, whereby said third filter may be designed to withstand voltages much less than the full power line voltage and whereby said first and second filters may be designed to withstand maximum voltages of the order of signaling voltages.
